Attorney

UNITED STATES PATENT OFFICE.

WILLIAM T. HENDERSON, OF OKLAHOMA, OKLAHOMA.

MOUNTING.

Specification of Letters Patent. Patented May 30, 1916.

1,185,315.

Application filed June 28, 1915. Serial No. 36,836.

To all whom it may concern:

Be it known that I, WILLIAM T. HENDERSON, a citizen of the United States, residing at Oklahoma, in the county of Oklahoma and State of Oklahoma, have invented certain new and useful Improvements in Mountings, of which the following is a specification.

My invention relates to mountings for eyeglasses and spectacles, and has for its essential objects the maintenance of a positive yet yielding grip upon the nose regardless of the particular contour of the latter; to afford comfort to the wearer; to insure a stable positioning of the glasses in a horizontal plane contemporaneously with affording yielding auxiliary nose bearing surfaces capable of assuming various angles relatively to the positive or positioning means; to afford a maximum capacity for adjustment; and to attain these objects in a strong and inexpensive structure.

To the recited and other ends my invention consists in such parts and combinations of parts as fall within the scope of the appended claims.

In the accompanying drawings which form a part of this specification, and where in like reference characters indicate like parts throughout the views, Figure 1 is a rear elevation of my novel mounting embodied in a pair of eyeglasses, portions of the lenses being broken away, Fig. 2, a plan view of one end of the bridge and the adjacent parts, Fig. 3, a section on line 3-3 of Fig. 1, and Figs. 4 and 5, detail views of the two constituent members of a guard.

In the drawings 1 represents the lenses, 2 the straps, 4 the bridge, including the flat tened supports or end portions 5 thereof, all of ordinary construction, in conjunction with which my invention is shown in the present instance.

The operative portions of both clamping devices of the guard being identical, a detailed description of one only will be given. The clamping device, in the form thereof herein shown, is of the so called "finger

piece" type comprising an operating arm 7 composed of flat bendable material terminating at its forward end in a finger piece portion 8, and provided intermediate its length with a perforation 9 to loosely receive the post 11 fixed in the support 5, around which is coiled the helical spring 14 whose ends 15 and 16 engage the adjacent strap and arm respectively. Integral with the rear end of the operating arm is an upwardly directed extension or arm 18 to whose upper end is attached a nose pad or bearing surface 20.

Pivotedly attached to an intermediate portion of the arm 18 is a guard arm 22 having upon its top and bottom nose pads or bearing surfaces 24 and 25, said arm being disposed at an angle to the plane of the lens and to the vertical plane of the arm 18, or forwardly inclined, so that its upper bearing surface 21 will be located intermediate the pad 20 and the bridge, as shown in Figs. 2 and 3. The ends of the guard arm, 22 have a transverse movement in opposite directions independently of the arms 7 and 18 as will presently appear. In this case the arm 22 is shown non-integral with the arm 18 and pivotally attached thereto. The attaching means shown consists of a bearing formed by a circular plate 28 connected by a U-shaped neck 29 integral therewith to an intermediate portion of the arm 18 with which it also is integral. The plate 28 is in parallelism with the latter arm, and the neck and plate originally constituted before bending an integral arm and a broad end portion respectively. It will, therefore, be noted that the members 7, 18, 28 and 29 are of inexpensive construction since they may be initially cut out from a flat sheet of metal and be subsequently bent into final form. The described bearing receives loosely a circular lug 31 upon the edge of an intermediate portion of the arm 22, and projecting rearwardly thereof, as shown in Fig. 5. Perforations 32 and 33 in the lug and plate respectively receive a pivot pin, screw, or rivet 35 fixed in the arm 18. To prevent ex

cessive rotary travel of arm 22, the lug 31 has a projection or stop 37 upon its periphery adapted to contact with the lower edge of the neck or finger 29.

5. It will be observed that the described mounting affords a maximum capacity for adjustment by reason of the fact that all of the constituent parts thereof are composed of bendable material; and that all 10 the arms are capable of being originally cut in only two pieces from a flat blank, thus reducing expense to a minimum.

In operation, the arms 18 are relied upon to anchor or positively position the lenses 15 in a horizontal plane, and lend themselves readily to manual adjustment for this purpose according to the breadth of the upper portion of the nose. At the same time the bearing surfaces on the arm 22 automatically accommodate themselves to the shape or contour of the adjacent portion of the nose, so that even were the lever 7 fixed relatively to the bridge rather than pivoted, there would still be to a certain extent a 25 combined fixed and yielding grip upon the wearer's nose due to the pivotal movement of the arm 22 relatively to the arm 18. The structure affords a comfortable but unusually tenacious grip.

30. I claim:

1. In a mounting, the combination with the support, of an operating arm on the support, a rocking guard arm carried by the operating arm and mounted to rock in the 35 plane of the arm at its point of connection thereto, and a bearing arm integral with the operating arm and co-operating with the rocking arm to engage a nose.

2. In a mounting, a support, an operating 40 arm on the support, an arm upon the first arm for anchoring the parts to a nose, and a guard arm carried by the operating arm and mounted to rock in the plane of the arm at its point of connection thereto and trans-

45 versely of the other arms and adapted to bear upon the sides of the nose.

3. In a mounting, the combination of a support, an operating arm on the support, an upright nose bearing arm upon the first 50 arm for anchoring the parts, and a guard arm carried by the operating arm inclined toward the support and tiltable transversely of the other arms adapted to bear upon the sides of the nose at a plurality of points 55 adjacent the point of engagement of the bearing arm.

4. In a mounting, the combination of a support, an operating arm on the support, a stationary nose bearing arm on the first 60 arm, and a guard arm connected intermediate its length to the bearing arm and mounted to rock in the plane of the arm at its point of connection thereto and transversely of the first arm.

5. In a mounting, the combination with 65 the support, of an operating arm on the support, an upright nose bearing arm rigid with the end of the first arm, and a guard arm connected to the bearing arm and mounted to rock in the plane of the arm at 70 its point of connection thereto and movable transversely of the first arm.

6. In a mounting, the combination with 75 the support, of an operating arm upon the support, an upwardly directed nose bearing arm upon the first arm, and a guard arm connected intermediate its length to the bearing arm and mounted to rock in the plane of the arm at its point of connection thereto and having its upper end intermediate the 80 bearing arm and the support.

7. In a mounting, the combination with 85 the support, of an operating arm upon the support, an upwardly directed nose bearing arm thereon, a pad on said nose-bearing arm, and a guard pivotally mounted upon the bearing arm and mounted to rock in the plane of the arm at its point of connection thereto and movable transversely of both arms.

8. In a guard, the combination with the 90 support, of an operating arm on the support, an upwardly directed arm integral therewith, a pad on said nose-bearing arm, a guard inclined toward the support and 95 pivotally mounted intermediate its length upon the nose-bearing arm, to rock in the plane of the operating arm at its point of connection thereto.

9. In a mounting, the combination with 100 the support, of a yielding operating arm pivotally mounted upon the support, a nose bearing arm integral with the operating arm, a pad thereon, a guard pivotally mounted upon the nose-bearing arm and mounted 105 to rock in the operating arm at its point of connection thereto movable transversely of both arms, and a spring carried by the support engaging the operating arm.

10. In a mounting, the combination with 110 the support, of an operating arm upon the support, a nose bearing arm integral with the first arm, a pad thereon, a U-shaped neck upon the nose-bearing arm, a plate on the neck forming with the nose-bearing arm 115 a bearing, a guard, a lug on the guard located in the bearing, and a pivot member connecting the lug and bearing.

11. In a mounting, the combination with 120 the support, of an operating arm on the support, a nose bearing arm on the first arm, a pad thereon, a U-shaped neck on the nose-bearing arm, a plate on the neck parallel with the nose-bearing arm, a guard, a lug on an intermediate portion of the guard 125 embraced between the plate and the nose-bearing arm, a pivot member connecting the plate, a lug upon the nose-bearing arm, and

a stop projection on the lug adapted to contact with the neck.

12. In a mounting, an operating arm bearing a rocking guard arm having upper and lower nose pads, and an anchoring pad.

13. In a mounting, an operating arm bearing a rocking guard arm having upper and lower nose pads and an anchoring pad, said guard arm being tiltable transversely with its travel intermediate the upper and lower nose pads.

14. In a mounting, an operating arm bear-

ing a rocking guard arm having upper and lower nose pads and an anchoring pad, said guard arm being tiltable transversely with its travel intermediate the upper and lower nose pads in opposite directions independently of the operating arm.

In testimony whereof I have affixed my signature in presence of two witnesses.

WILLIAM T. HENDERSON.
